UNITED STATES PATENT OFFICE.

ALBERT F. SCHWERD AND ASA W. EMRICK, OF ALLEGHENY,
PENNSYLVANIA.

DESIGN FOR A COLUMN-SHAFT.

SPECIFICATION forming part of Design No. 31,159, dated July 4, 1899.

Application filed May 8, 1899. Serial No. 716,033. Term of patent 14 years.

To all whom it may concern:

Be it known that we, ALBERT F. SCHWERD and ASA W. EMRICK, citizens of the United States of America, residing at Allegheny, in the county of Allegheny and State of Pennsylvania, have invented a certain new and useful Design for Column-Shafts, of which the following is a specification, reference being had therein to the accompanying drawings.

10 The herein-described design for column-shafts relates in general to the orders of architecture known as "Grecian Doric," "Roman Doric," "Corinthian," "Ionic," and "Doric," and more particularly to the Roman Doric of the Corinthian order.

15 Figure 1 is a front elevation of our design in perspective. Fig. 2 is a top plan view thereof with the capital removed.

The leading feature of our design consists 20 in the outer configuration of the column-shaft 1, having a series of raised scalloped surfaces 2, connecting with concave sides 3 and forming flat ridges 4, which design is repeated circumferentially of the column-shaft, extending 25 ing from the stylobate 5 to the capital 6.

A further feature of our design consists in the crenelations 7, formed on the top thereof.

The raised scalloped surfaces 2 are semicircular in their outer contour and meet the concave sides 3 alternately at the termination of 30 the arc of the raised scalloped surfaces and at the termination of the crenelations 7. The raised scalloped surfaces 2, semicircular in their outer contour, the concave sides 3, and the flat ridges 4 fall within the outer contour 35 lines of the column, thus presenting to the eye the combined effects of a smooth circular outline and a scalloped outline within it. The top crenelations 7 extend radially from the inner to the outer face of the column and in 40 outline harmonizing with the flat ridges and concave sides arranged on the exterior of the column.

What we claim is—

The design for a column-shaft, as herein 45 shown and described.

In testimony whereof we affix our signatures in the presence of two witnesses.

ALBERT F. SCHWERD.
ASA W. EMRICK.
